DESIGN FOR A FOUNTAIN PEN

Joseph Starr, Chicago, Ill., assignor to The Conklin Pen Company Inc., Chicago, Ill., a corporation of Illinois

Application April 3, 1947, Serial No. 138,132

Term of patent 14 years

(Cl. D74—17)

To all whom it may concern:

Be it known that I, Joseph Starr, a citizen of the United States of America, residing at Chicago, in the county of Cook and State of Illinois, have invented a new, original, and ornamental Design for a Fountain Pen, of which the following is a specification, reference being had to the accompanying drawing, forming part thereof.

Fig. 1 is a front elevational view of a fountain pen showing my new design and arranged for writing;

Fig. 2 is a side elevational view;

Fig. 3 is a rear elevational view;

Fig. 4 is a front elevational view with the parts separated; and

Fig. 5 is a front elevational view with the cap over the writing end.

I claim:

The ornamental design for a fountain pen, substantially as shown.

JOSEPH STARR.
